Hammond, Ind., a corporation of Indiana

Application July 31, 1946, Serial No. 687,297

5. Claims. (Cl. 164—87)

1

The present invention relates to spacing tables, and, more particularly, to a spacing table for handling I-beams which are to be worked on by punches and presses.

In the use of I-beams certain operations must be performed to fit the I-beam for the particular use to which it is to be applied. In the instance of large structural shapes, I-beams have the flanges and webs punched for the use of rivets, bolts, and auxiliary plates. To perform such operations on I-beams, there is generally employed a relatively-large punch which is provided with a set of punches for the I-beam flanges and another set of punches for the web. In order to punch the web, the I-beam is placed on a spacing table having a plurality of spaced-apart stations, each provided with the necessary support rollers so as to position the I-beam horizontally so that it may be moved periodically into proper spaced position relative to the punches of the punch press. In order to punch the flanges it has long been customary to employ a plurality of stations, each provided with a large roller mounted on an adjustable support. Thus far, with each different size and weight of I-beam it has been necessary to adjust the individual stations which serve to support the I-beam on its lower flanges. Obviously, of course, such manner of handling the I-beam has the disadvantage of requiring accurate adjustment of each support at each station. It, therefore, would be desirable to provide a different manner of supporting the I-beam so as to avoid the necessity of individual adjustment of each support whenever different size I-beams are to be worked on.

In accordance with the present invention, it is proposed to overcome the disadvantage heretofore encountered in the handling of I-beams by supporting the I-beam on the underside of the flange in the proximity of the web. The underside of the flange would then be fitted to the punch so that the underside coincides with the top surface of the punch die. In order to insert into the spacing table an I-beam supported in this manner, there is provided, in accordance with the present invention, a pivoted support arm at each station which is interconnected with a unitary control means. The unitary control means moves the pivoted support outwardly for the insertion and removal of the I-beam.

It, therefore, is the object of the present invention to provide an improved spacing table for handling I-beams in their vertical position.

It is a further object of the present invention to provide an improved spacing table for use with

2

punches and presses which will handle a plurality of sizes and weights of I-beams without adjustment.

Other and further objects of the present invention subsequently will become apparent by reference to the following description taken in conjunction with the accompanying drawings wherein:

Figure 1 shows portions of the trailing and pulling spacing tables which cooperate with a punch or press;

Figure 2 is a cross-sectional view across one of the spacing tables as seen in the direction of the arrows along the line 2—2 of Figure 1; and

Figure 3 is a cross-sectional view as seen in the direction of the arrows along the horizontal line 3—3 of Figure 2.

In Figure 1 there is shown a dotted line representation 10 which indicates a punch press of the type which is provided with a plurality of sets of dies for performing work on the web and the flanges of an I-beam 11. Mounted to the left of the punch or press 10 in Figure 1 there is a trail end spacing table which is constructed in accordance with the present invention. The trail end spacing table is composed of a plurality of sections 12 extending between spaced support stations 14. In one embodiment, the spacing table for the trail end consisted of six sections and seven support stations. Adjacent each end the penultimate station is provided with a fluid-operated piston 16 in a cylinder secured to the support station and arranged to actuate a shaft 18 which extends between all of the stations.

On the pull end of the press, as seen in Figure 1, another spacing table is provided which has in one embodiment six similar sections 20, such as that shown and which has an additional section for supporting a gripping mechanism which is carried on a plurality of rails 22 which overhang each end of the spacing table by an amount of the order of that illustrated in Figure 1. The pull end spacing table, therefore, has a plurality of support stations 24 so that for a six-section pull end table there would be seven similar support stations 24 and an additional support station which carries the last section of the rails 22. This construction in one embodiment resulted in a trailer end table which had an overall length of about fifty-two feet and a pull end table which had an overall length of about sixty-five feet.

By referring to Figures 2 and 3, the details of the structure will readily become apparent. Each station 14 has three foundations 26, 28, and 30, 55 which carry vertical I-beams 32, 34, and 36. The

upper end of the intermediate I-beam 34 carries a horizontal longitudinally-extending angle or L-beam 38, upon which is supported a bearing housing 40. The beam 38 is supported by the upper extremity of the I-beam 34, which also carries support brackets 39 secured to the upper end thereof and which may be welded to the I-beam 34 and to the horizontal beam 38. The bearing housing 40 supports one end of a shaft 42, which carries a plurality of adjustable support rollers 44, which are adjustable along the axis of the rod 42. The other end of the rod or shaft 42 is supported in a bearing housing 46, which is mounted on a support ledge 48 formed by cutting inwardly a short distance from the upper extremity of the I-beam 36. The upper extremity of the I-beam 36 carries a longitudinally-extending angle or L-beam 50 which may be further supported by brackets 52 mounted on opposite sides of the web of the I-beam 36. The brackets 52 preferably are secured to the web of the I-beam 36 by welding and the angle iron 50 is also secured in position by welding to the I-beam 36.

The adjustably-positioned wheels or rollers 44, carried by the shaft 42, engage the web of an I-beam so that the I-beam may be moved in a horizontal position to and from the punch or press which is to perform operations on the web of the I-beam. The tops of the rollers 44 are aligned so as to be contiguous to a plane passing through the top surface of the dies in the punch press 10. This manner of supporting the I-beam in a horizontal position is similar to the manner of supporting the I-beam heretofore employed in the prior art.

In accordance with the present invention, there is provided an improved manner of supporting the I-beam in a vertical position by providing at each station a support arm 54 which is mounted on the angle beam 38. The arm 54 is rigidly secured in position and is of a suitable configuration so as to extend upwardly in a curved direction so as to have a horizontal axis for a support roller 56. The support roller 56 engages the underside of the flange of an I-beam in the proximity of its web. Preferably, the support roller 56 is mounted on a shaft portion of the arm 54 by means of suitable anti-friction bearings, and the surface of the roller 56 preferably is crowned.

Interconnecting the I-beams 32 and 34, adjacent the foundations 26 and 28, is a support or horizontally-arranged I-beam 58, which, at an intermediate point, is provided with a suitable bearing member 60, which extends on opposite sides of the web of the I-beam 58. The bearing member 60 carries a shaft 18, which extends throughout the length of the spacing table, as is apparent from the showing in Figure 1. Adjacent one side of the I-beam 58 there is fixedly mounted on the shaft 18 a support arm 64, which extends outwardly from the shaft 18 and then upwardly in a vertical direction and, finally, in a curved direction so as to have a horizontal shaft portion which supports a roller 66. The roller 66 is similar to the roller 56 and, preferably, is mounted on the arm 64 by a suitable bearing. From the solid line representation in Figure 2, it is apparent that the arm 64 cooperates with the arm 54 to support, by means of the rollers 66 and 56 respectively, the undersides of the flange of an I-beam in the proximity of the web. The crowned surfaces of the rollers 56 and 66 are tangential to a horizontal plane which passes

through the surface of the dies on the punch 10 in Figure 1.

On the opposite side of the I-beam 58 the shaft 18 has secured thereto a crank or lever 68 which is carried to the shaft 18 by a key 70. A similar key or other means may likewise be provided for securing the support arm 64 to the shaft 18.

Mounted between the I-beams 34 and 36 is a horizontally-arranged I-beam 72, which carries at one side a support plate 74. Mounted on the support plate 74 is a fluid-operated piston and cylinder 16 which has a piston rod 76. The piston rod passes through a guide 78, which also is mounted on the support plate 74. The outer extremity of the piston rod 76 is connected to a link 80 which in turn engages a bell crank which is mounted on a shaft 84 which is carried by a suitable bearing member 86 mounted on or supported by the I-beam 72. The bell crank 82 is connected by a link 88 to the outer extremity of the crank or lever 68. Actuation of the fluid cylinder and piston 16, which may be either air or hydraulically operated, moves the levers and links between the piston rod 76 and the shaft 18 to the dotted line position shown in Figure 2, thereby to move the support arm 64 through an arc to the dotted line position shown. In the dotted line position it will be noted that the support rollers 66 are substantially beneath an angle or L-beam 90, which is mounted on the upper extremities of the I-beam 32. In this position there is ample space between the rollers 56 and 66 to provide for the insertion and removal of I-beams.

The horizontal beams 50 and 90 serve as support tracks or runways for an I-beam gripping mechanism 91 which is carried by a suitable carriage having rollers 92. The gripping mechanism 91 engages the I-beam or material to be moved so that the desired linear movement or spacing of the I-beam or material may be obtained in order to perform a succeeding operation on the I-beam.

The gripping mechanism 91 is moved linearly by a hand wheel 94 which is connected to a suitable mechanism for positively propelling the carriage 91. The propelling mechanism may comprise a gear which engages a rack secured to the spacing table. The mechanism 91 is provided with a suitable gripping apparatus (not shown) for engaging the web of the I-beam when it is supported by the rollers 44, and with another gripping mechanism, as shown in Figure 2, for engaging the flanges of the I-beam when it is supported by the rollers 56 and 66.

This latter mechanism includes forwardly extending support members 96 which carry a slotted bar 98, and a right and left hand threaded shaft 100. The outer extremity of the shaft 100 carries an adjusting wheel 102 for adjusting the position of a pair of gripping members 104. Each gripping member 104 may be in the form shown which is a knife edge which engages opposite edges of the top flanges of the I-beam 11. Other suitable flange engaging members may be employed instead of the knife edges which however should engage on opposite sides substantially only relatively small portions of the edges of the I-beam flanges. The flange gripping members are supported by blocks 106 which have threaded apertures for the shaft 100 and have T-shaped members supported within the slot of the cross bar 98. Such an arrangement obviates the necessity of a more complicated apparatus for engaging the I-beam by the web portion when sup-

ported vertically by the rollers 56 and 66 on the arms 54 and 64.

The apparatus shown and described in conjunction with Figures 2 and 3 has been specified as a cross-sectional view through a trail end spacing table. The movement of the material as seen in Figure 1 is from left to right. With the exception of the extreme right end section of the pull end table, the construction of the pull end table is similar to that described for the trail end table, and, hence, the cross-sectional views in Figures 2 and 3 would merely be reversed if a cross-sectional view was taken looking toward the right in a plane spaced slightly to the left of the corresponding actuating piston 16a of the pull end table.

Since the parts on the pull end spacing table are similar to the parts on the trail end spacing table, they have been given corresponding reference characters with the addition of the letter *a*. The letter *a* will, therefore, indicate that the arrangements are similar, but in reversed position.

It was previously mentioned that the pull end spacing table had an overhanging portion 22 of the rails which support a gripping mechanism, and, furthermore, at the extreme right end had an additional section which merely supported the rails to support the gripping mechanism. The additional section is provided so that the gripping mechanism may be moved out of the way of the I-beam when it is to be removed from the pull end table.

It has been mentioned that the support arms 64 are moved out angularly for the insertion and withdrawal of the I-beam 11. Obviously, on the trail end table the arm 64 is moved outwardly in order to receive the I-beam, whereupon it is moved toward the punch 10, and, subsequently, moves past the punch 10 onto the pull end table. Accordingly, the corresponding arm 64a of the pull end table will, subsequently, be opened in order to permit the I-beam 11 to be removed therefrom.

From the foregoing description, it will be seen that each spacing table consists of a plurality of stations having vertical support members, such as the I-beams 32, 34, and 36. On each table two air or hydraulic pistons and cylinders are provided. It will also be appreciated that in accordance with the invention it is possible to rapidly supply to the press 10 different size beams without the necessity of laboriously adjusting the level or height of each support station for carrying the I-beam in a vertical position. The fluid-operated piston and cylinder 16 may be readily controlled from a control panel near the press 10. This greatly increases the rate of production of the work to be performed on the I-beams, since not infrequently the holes to be punched in such I-beams may be of the same dimensions and same arrangements for different sizes or weights of I-beams. Hence, in accordance with the present invention, a relatively simple to operate spacing table may be constructed.

While for the purpose of illustrating and describing the present invention the drawings have illustrated a particular embodiment, it is to be understood that the invention is not to be limited thereby since such variations in the structural arrangement and the components employed are contemplated as may be commensurate with the spirit and scope of the invention set forth in the following claims.

I claim:

1. A spacing table for cooperation with a machine for performing work on the flanges of an I-beam comprising a series of linearly-spaced support stations, each being interconnected with an adjacent station by horizontal bars and a rotatable shaft, each support station having a stationary horizontal portion provided with a roller for engaging the underside of the flange of the I-beam in the proximity of the web, each station having a pivoted support secured to said shaft and having an extremity provided with a roller for engaging the underside of the flange of the I-beam on the opposite side of said web, and means located near the ends of said shaft for actuating said shaft.

2. A spacing table for cooperation with a machine for performing work on the flanges of an I-beam comprising a series of linearly-spaced support stations, each support station being interconnected with an adjacent station by a rotatable shaft, each support station having a stationary support provided with a horizontal portion supporting a roller for engaging the underside of the flange of an I-beam in the proximity of the web, each station having a pivoted support secured to said shaft and having a substantially horizontal extremity provided with a roller for engaging the underside of the I-beam flange on the opposite side of said web, said rollers being located so that a plane contiguous to the top surface of said machine is tangential to the periphery of said rollers, and fluid-operated power means located adjacent the penultimate support stations for actuating said shaft.

3. A spacing table for cooperation with a machine for performing work on the flanges of an I-beam comprising a series of linearly-spaced support stations interconnected by a rotatable shaft, each support station comprising a pair of fixed vertical spaced supports, one of said supports having a fixed support arm provided with a horizontal shaft portion supporting thereon a roller, a horizontal member interconnecting said vertical supports, a bearing mounted on said horizontal member, said shaft being mounted in said bearing, a pivoted arm mounted on said shaft and having a horizontal shaft portion supporting thereon a roller, said rollers on said pivoted arm and said fixed support arm being arranged to engage the underside of the flange of an I-beam adjacent on opposite sides of the web thereof, and means adjacent the ends of said shaft for actuating simultaneously the pivoted arms at said support stations.

4. A spacing table for cooperation with a machine for performing work on the flanges of an I-beam comprising a series of linearly-spaced support stations each having a pair of fixed vertical spaced supports one of said supports having a rigid support arm provided with a horizontal shaft portion having thereon a roller adapted to engage the underside of the flange of an I-beam adjacent the web thereof, a horizontal I-beam interconnecting said vertical supports, a bearing mounted on said I-beam, a plurality of horizontal beam members interconnecting the supports of said stations, a shaft mounted in said bearing and extending through similar bearings in other stations, a pivoted arm mounted on said shaft and having a horizontal shaft portion supporting thereon a roller adapted to engage the underside of the flange of an I-beam adjacent the other side of the web engaged by said first-mentioned roller, and power-operated

means adjacent the ends of said shaft at the penultimate stations for simultaneously actuating the pivoted arms at said support stations.

5. The combination comprising a spacing table having a plurality of spaced support stations for supporting vertically an I-beam by its upper flange, a plurality of horizontal bars interconnecting said stations, a carriage movably mounted on said horizontal bars, means carried by said carriage for engaging one of said bars to drive said carriage therealong, means carried by said carriage for gripping the edges of the top flange of a vertical I-beam including a horizontal guide member, a shaft having oppositely threaded portions, a pair of I-beam flange engaging members

mounted on said guide member and said threaded shaft for engaging relatively small opposite edge portions of said I-beam flange, and means for actuating said threaded shaft to adjust the positions of said engaging members.

LOWELL CRAWFORD BEATTY.
